HANDBAG

Claremont Robert Morris, New York, N. Y.

Application December 31, 1942, Serial No. 470,863

2 Claims. (Cl. 150—29)

This invention relates to handbags, and particularly to handbags such as are carried by women and such as are provided with hinged frames at the part of the bag which opens and closes.

An object of the invention is to provide a handbag with improved means enabling the same to be changed in appearance to conform to the attire or whim of the user.

A further object of the invention is to provide a slip cover for the bag and improved means for gripping the same in place.

Another object of the invention is to combine the said gripping means with the frame so as to open and close therewith in normal use of the bag and have the appearance of being part of the frame.

Again, an object of the invention is to provide an assembly of adequate simplicity and of ease of manipulation whereby any woman may make substitution of slip cover and entirely without use of any tools to accomplish the purpose.

Yet again, an object of the invention is to enable the handbag to be utilized as a usual type of handbag with an over-top handle, or utilized as an under-arm bag without a handle or utilized as a shoulder-supported handbag.

Still further objects of the invention will appear as the description progresses, both by direct recitation thereof and by implication from the context.

Referring to the accompanying drawing in which like numerals of reference indicate similar parts throughout the several views;

Figure 1 is a perspective view of a handbag shown closed and embodying the features of the present invention;

Figure 2 is an end view of an upper portion of the bag and showing the same partly open;

Figure 3 is a similar end view, showing the clamping or gripping frames in releasing positions and the slip cover somewhat lower than in assembled position;

Figure 4 is a perspective view of a part of the corrugated spring or resilient member utilized with the gripping frames; and

Figure 5 is a cross-sectional view through one of the gripping frames, resilient member and showing a removable ornament applied thereto.

In the specific embodiment of the invention illustrated in said drawing, the reference numeral 10 designates the pouch of a handbag the edges whereof at the opening for the pouch are secured as usual in hinged frame members 11, 12. For convenience of designation, one of these

frame members will be arbitrarily called the rear frame member 11 and the other will be called the front frame member 12. Each frame member has the usual top reach from the ends of which depend leg portions or end reaches the basal parts of which are directed toward and overlap each other and hinged where overlapped upon hinge-pins 13. Any suitable catch or lock 14 is provided on one frame member, as 11, to engage the other frame member 12 and hold the frame closed as usual, but releasable to enable the user to unlatch the same and swing the frame members apart when it is desired to gain access to the interior of the pouch.

15 A slip cover 15 is provided to overlie the exterior of the pouch 10, said slip cover being of appropriate size and shape to substantially fit the said pouch and maintained by the reinforcement afforded by the pouch to fill out the shape of a handbag. The slip cover may accordingly be made of highly flexible and light-weight material such as silk, satin, cotton or wool fabrics, this feature enabling the slip cover to match, harmonize or be of the same material as a user's garment. The slip cover is removable and replaceable and a user may have as many different slip covers as desired and thus be enabled to change the appearance of handbag being carried by utilization of the desired slip cover on the one handbag.

30 Provision of suitable means to hold the edges of the slip cover corresponding to the edges of the pouch held by the frame is incorporated as part of the structure and of the present invention. In carrying out a physical embodiment of this feature, clamping or gripping frames 16 are provided with one gripping frame hinged to the rear frame member 11 and another gripping frame hinged to the front frame member 12. 35 These gripping frames each have a top reach and appropriate length and cross-section to conform to the top reach of the frame member to which hinged. From the ends of the top reach of each gripping frame depend leg portions 17 the lower 40 or basal parts whereof are directed toward and overlap each other in assembled position and the overlapping portions having holes 18 therein adapted to register and to be applied to the protruding end of hinge-pin 13 heretofore located as 45 also constituting the hinging means for the main frame members. The user may apply or remove the gripping frames on or from the hinge pins, the normal resiliency of the said gripping frames retaining the same on the pivot pins until adequate effort is exerted by the user to remove them

therefrom. During the ordinary opening and closing of the bag, the main frames and the gripping frames remain closely associated in pairs and swing open and closed on the common pivot line represented by the aligned pivot pins.

Hinges 19 on the upper reaches of the gripping frames engage permanently in slots in the upper reaches of the main frame, and thus, when the end legs are released from the pivot pins, the gripping frames can be swung with respect to the main frame members as shown in Figure 3. This gives opportunity to situate the edges of the slip cover to underlie the said gripping frame which can then be swung back to gripping position. To assure a tight grip upon the margin of the slip cover, a gripping member, shown as a corrugated leaf spring 20 is carried on the inside face of the gripping frame and retained associated therewith in any suitable manner as by spot welding at one or more points. As a means for further distinctive characterization of the bag to conform to a desired color scheme or otherwise harmonize with the user's attire, a removable ornament 21 may be applied to the top reach of the gripping frame. As shown particularly in Figure 5, a hook 22 on said ornament may be inserted through a prepared hole in the gripping frame and the inner part pressed to said gripping frame by the gripping spring for holding the ornament against inadvertent removal. When the pressure is relaxed by swinging the gripping frame to its releasing position of slip cover as shown in Figure 3, the ornament hook will be sufficiently released to permit the user to change the ornament if desired.

The construction above described is conducive to utilization of an adjustable and removable strap handle or support 23 suitable punctured at 24 to engage upon pivot pins 13. The strap is applied to the pins before applying the legs of the gripping frame thereto which accordingly retain said strap from inadvertent disengagement therefrom. The strap may be applied to provide only a short loop thereof across the bag and thus act as a hand support for the bag, or may be applied with a long loop of strap exposed above the bag for use as a shoulder support for the bag. The lower ends of the strap are situated between the pouch and slip cover, thus not being exposed in either mode of use and not dangling when the strap is used as a short loop and hand support for the bag.

It may be particularly pointed out, in conclusion, that the gripping frames have a general position and appearance as part of the normal type of bag frame so that the incorporation of my invention in a handbag does not give an impression of change from conventional constructions of bags, and yet a person may readily and without use of tools change the slip cover to other colors or patterns of material for the finish on the bag, and at the same time may change the ornament 21. Operation of the bag to gain access thereto or to close the same like-

wise follows conventional bag construction and use. In addition, the handle or support construction is such that the same may be used either long or short or may be entirely removed

5 and the bag then used as a conventional under-arm bag. The invention contemplates other structural embodiments and is not restricted to the specific details arbitrarily selected as the selected form for purposes of illustration and de-

10 scription herein.

I claim:

1. A handbag comprising a bag frame having legs hinged at their lower ends and having a cross head connecting the upper ends of said legs, a pouch member having edges thereof overlapping said legs and cross head of the frame, a gripping frame having a cross head and legs each having edge faces overlapping corresponding edge faces of the bag frame and each having front faces substantially the area of the corresponding front faces of the bag frame for overlying the same in substantial registration therewith, said cross heads of the bag frame and of the gripping frame being longitudinally hinged thereby enabling the legs of the gripping frame to be swung away from the lower ends of the legs of the bag frame for gripping the edge of the pouch member between the said cross heads, means for releasably securing the lower ends of the legs of the bag frame, and a corrugated spring coextensive with the cross head and legs of said frames and interposed between the bag frame and gripping frame and gripping the edge of the pouch member where said edges of the pouch member overlap said legs and cross head of the bag frame.

2. A handbag comprising a bag frame having legs hinged at their lower ends and having a cross head connecting the upper ends of said legs, a pouch member having edges thereof overlapping said legs and cross head of the frame, a gripping frame having a cross head and legs each having edge faces overlapping corresponding edge faces of the bag frame and each having front faces substantially the area of the corresponding front faces of the bag frame for overlying the same in substantial registration therewith, said cross heads of the bag frame and of the gripping frame being longitudinally hinged thereby enabling the legs of the gripping frame to be swung away from the lower ends of the legs of the bag frame for gripping the edge of the pouch member between the said cross heads, means for releasably securing the lower ends of the legs of the bag frame, said releasable means comprising hinge pins for the bag frame projecting outwardly therefrom and receiving said lower ends of the gripping frame thereon, and a handle also carried on said hinge pins, said legs of the gripping frame being situated outside of the handle and retaining the said handle on the hinge pins.

CLAREMONT ROBERT MORRIS.
